UNITED STATES PATENT OFFICE

PAUL WILSING, OF DUISBURG, GERMANY, ASSIGNOR TO DEMAG AKTIENGESELLSCHAFT, OF DUISBURG, GERMANY

ELECTRIC HOISTING GEAR

Application filed July 13, 1927, Serial No. 205,428, and in Germany March 3, 1927.

The present invention relates to hoists that are adapted to a variety of practical requirements such as for suspension in a stationary position, for being moved in a horizontal plane, or for being mounted upon travelling crabs; and the invention has among its objects to cause a second rope provided with a load hook or block to be lowered as the other rope from which a load is suspended, is raised, whereby the hoist after lowering or raising one load is immediately available to lower or to raise another; and to effect the automatic braking of the hoist gear by the armature of the operating electro-motor, which for the purpose is axially movable.

The features of the invention are herein-after set forth by reference to the accompanying drawings in which

Figures 1 and 2 relate to one construction embodying the invention in which Figure 1 is a longitudinal section through a hoisting gear, and

Figure 2 is an end view corresponding to Figure 1, the left hand side of the figure being a part front elevation of the casing 5, and the right hand side of the figure being a part cross-section through the said casing,

Figure 3 relates to another construction embodying the invention and is a front elevation of the casing of a hoist similar in construction to that illustrated in Figures 1 and 2, the casing being provided with lateral pulleys, and

Figure 4 relates to another construction embodying the invention and is a side elevation of a hoist similar in construction to that illustrated in Figures 1 and 2, in which the ropes are provided with blocks.

The stationary part 2 of the motor is provided in the casing 1, and the rotor shaft 3 of the electro-motor is mounted at 4^a on the left in the partition wall 4 of the gear casing 5. The shaft has mounted upon it at its forward end, a pinion 6, which engages in a corresponding set of internal teeth of the toothed wheel 7. The latter is connected with the pinion 8 upon the shaft 9, and the toothed wheel 7 and pinion 8 are preferably made integral. The pinion 8 engages the two toothed wheels 10, which are connected with the driving pul-

leys 11. Here again one of each of the toothed wheels 10 and a driving pulley 11 are formed integral. The rope 12 is wound a number of times around the driving pulleys 11, the two ends of the rope being provided with load hooks 13 loaded by weights 12^a.

The casing 5 is disposed in a position close to the pulleys 11 in such manner that it is impossible for the rope to leave them, and thus it is unnecessary to provide a special rope guide.

As the rope always passes out of the casing at one and the same position, the guiding slots 15 may be made very narrow. On the other hand, by the construction according to the present invention the slots may extend laterally over almost the whole periphery of the pulleys, so that the ropes may pass out of the casing at any desired angle and even horizontally.

A brake cone 16 is provided upon the rotor shaft of the motor 2, the opposing cone 17 being formed by the cover plate 18 of the casing.

The motor is provided with the axially movable armature 2^a, so that when the current is cut off the rotor moves to the right under the action of the spring 19 and is thus braked.

The spring 19 presses against a ring 19^a which in turn presses against the rollers 4^b of the bearing 4^c. The radial bearing is thus at the same time used for absorbing the comparatively small axial pressures.

In order to provide a sufficient distance between the ropes for cumbersome loads, they may be guided, as illustrated in Figure 3, over lateral pulleys 14 which are mounted in the brackets 19 of the casing.

According to the construction illustrated in Figure 4 each of the rope ends that extend from opposite sides of the hoist is fastened to the casing by suitable securing means as indicated at 20.

Blocks 21 may be suspended in loops thus formed by the respective ropes. The lower block disposed in its lowermost position is not shown in Figure 4 in order to make the drawing simpler. The respective loads are raised by the hooks, at only half the speed

compared with the hoisting gear in which the loads depend directly from the rope ends.

The motor is started up and stopped in any suitable known manner from the floor level; 5 it drives the two pulleys 11 simultaneously and uniformly. The length of the rope that is wound around the two pulleys is adapted to the hoisting distance. As it is provided at both ends with load hooks, eyes, claws or 10 the like, a load can be raised at each operation of the rope by the upwardly moving end of the rope, during which time the other end of the rope is lowered with or without a load.

I claim:

15 1. An electric hoist consisting in combination of a casing, an electro-motor and two juxta-posed driving and load sustaining pulleys within the said casing, the said pulleys being mounted upon axes substantially parallel 20 and in the same plane as the electro-motor shaft, a flexible load suspension member wrapped around the said pulleys, the respective ends of which member bear load-engaging means and depend at the opposite outer 25 sides of the said pulleys and when unloaded are respectively of such weight as to subject the said flexible member to tension, a counter-shaft supported within said casing between the said pulleys, and gearing upon said 30 countershaft transmitting the drive of the electro-motor to the two pulleys, substantially as hereinbefore described.

2. An electric hoist according to claim 1, comprising a casing in two detachable sections, one section enclosing the electro-motor and the other section the two pulleys and the countershaft with the gearing thereon, substantially as hereinbefore described.

3. An electric hoist consisting in combination of a casing, an electro-motor and two juxta-posed driving and load sustaining pulleys within the said casing, the said pulleys being mounted upon axes substantially parallel 40 and in the same plane as the electro-motor shaft, a flexible load-suspension member wrapped around the said pulleys, the respective ends of which member bear load-engaging means and depend at the opposite outer 45 sides of the said pulleys and when unloaded are respectively of such weight as to subject the said member to tension, a countershaft supported within said casing between said pulleys, and gearing upon said countershaft adapted to cause simultaneous rotation of the 50 said pulleys on operation of the said electro-motor, the said gearing comprising a gear wheel with internal teeth, a pinion on the shaft of the electro-motor engaging the said gear wheel, and gear wheels provided 55 respectively on the said driving pulleys and each engaging the pinion on the countershaft, substantially as hereinbefore described.

4. An electric hoist consisting in combination of a casing, an electro-motor having an 60 axially movable rotor and shaft, a brake mem-

ber rigidly mounted on said shaft, a co-operating brake member in fixed relation to the said casing, a spring adapted to move the said shaft axially to engage the brake members, two juxta-posed driving and load-suspension 70 pulleys within said casing, said pulleys being mounted upon axes substantially parallel and in the same plane as the electro-motor shaft, a flexible load-suspension member wrapped around the said pulleys, the respective ends 75 of which member bear load-engaging means and depend at the opposite outer side of the said pulleys and when unloaded are respectively of such weight as to subject the said member to tension, a counter-shaft supported 80 within said casing between the said pulleys, and gearing upon said countershaft transmitting the drive of the electro-motor to the two pulleys, substantially as hereinbefore described.

5. An electric hoist consisting in combination of a casing formed in two detachable sections, an electro-motor mounted in one section of the said casing, two juxta-posed driving and load-sustaining pulleys disposed 90 within the second section of the said casing, the said pulleys being mounted upon axes substantially parallel and in the same plane as the electro-motor shaft, a flexible load-suspension member wrapped around the said 95 pulleys, the respective ends of which member bear load-engaging means and depend on the opposite outer sides of the said pulleys, and when unloaded are respectively of such weight as to subject the said member to tension, a 100 countershaft disposed between the said pulleys within the second section of the casing, and gearing upon the countershaft for transmitting the driving from the electro-motor to the said pulleys, substantially as hereinbefore described.

6. An electric hoist according to claim 5, comprising an electro-motor with axially movable rotor and shaft, a brake member rigid upon the said shaft, a cover plate to the 110 section of the casing containing the electro-motor, a brake surface upon the said cover plate, and a spring tending to move the shaft and rotor axially to engage the brake members, substantially as hereinbefore described. 115
